AUTOMATIC ICE-MAKING MACHINE

Walter G. Ribeiro, Camden, N. J.

Application April 25, 1949, Serial No. 89,407

9 Claims. (Cl. 62—105)

1

The present invention relates generally to ice-making equipment and it relates more particularly to certain new and useful apparatus for automatically performing the various steps required in producing ice on a commercial scale.

An object of the present invention is to provide certain new and useful apparatus for producing ice. Another object of the present invention is to provide a certain new and improved machine which will automatically perform the filling, freezing, thawing and dumping operations required in producing ice on a commercial scale. Still another object of the present invention is to provide an ice-making machine having novel means for automatically filling an ice can with a predetermined amount of water to be frozen. A further object of the present invention is to provide novel means for lowering an ice can into a freezing-tank and for thereafter raising the can from the freezing-tank, permitting it to drain back into the tank, and subsequently spraying the can with thawing water while preventing dilution of the brine in the freezing-tank by the spray-water.

A still further object of the present invention is to provide novel hoist, switch and timing mechanism in an automatic ice-making machine which will permit an open-top can filled with water-to-be-frozen to remain partly immersed in generally upright position in a freezing-tank for a predetermined period of time; and which will thereafter tilt the can to a generally horizontal but somewhat downwardly-inclined position above the freezing-tank while permitting drainage of the brine back into the ice tank; and which will thereafter spray the can with thawing water for a predetermined period of time sufficient to loosen the ice-block in the can while draining off the thawing water during spraying and for a predetermined period of time thereafter to prevent dilution of the brine in the freezing tank; and which will thereafter dump the loosened ice-block from the can by gravity; and which will thereafter lower the empty can to its vertical position partly immersed within the freezing-tank; and which will thereafter fill the ice can with water-to-be-frozen to a predetermined level; and which will thereafter repeat the cycle of freezing, spraying, draining and dumping operations.

Other objects and advantages of the present invention are apparent in the following detailed description, appended claims and accompanying drawings.

In freezing ice commercially, it is customary to mount a number of open-top ice cans in a cradle or the like which is raised and lowered,

2

in vertical position, by a hoist mounted on an overhead track so that the water-filled ice cans can be partly immersed in a freezing-tank, and, so that, after the water in the cans has been frozen, the cradle can be hoisted out of the tank and maintained in elevated position to permit the brine on the outside of the cans to drain back into the freezing-tank, after which the cans are moved horizontally to a dumping station at which the cans are lowered into generally horizontal position with the open ends tilted somewhat downward, after which the cans are sprayed with thawing water to loosen the ice-blocks which eventually slide free. Conventional mechanism of the type described above is disclosed, for example, in Bright Patent 1,755,203. This conventional construction, while heretofore widely employed, has been relatively expensive in that it requires a sizable amount of manual labor and supervision in the filling, lowering, raising, moving, thawing, dumping, and re-filling operations. In addition, the cans are frequently left in the freezing-tank for longer-than-necessary periods due to improper or inaccurate supervision which results in an excessive consumption of power since no useful work is accomplished by the freezing-tank after the water in the individual ice cans has been fully frozen.

According to the present invention, there has been developed, for the first time, an ice-making machine which will perform the filling, freezing, thawing, draining and dumping operations fully automatically and in an appreciably smaller space and without the need for any manual labor and with appreciable savings in power consumption, as well as time.

The present invention also contemplates a fully automatic machine for quick-freezing ice in relatively thin ice cans in a fraction of the time normally required in making ice commercially.

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

55 Figure 1 represents a perspective view of one embodiment of the present invention, parts being broken away better to reveal the construc-

tion thereof—the ice-cans being shown in elevated dumping position and the water reservoir being shown in filled position.

Figure 2 represents a perspective view, with parts broken away, showing the rear of the embodiment of Figure 1—the ice-cans being shown in lowered position partly immersed within the freezing-tank.

Figure 3 represents a fragmentary side elevational view showing the limit-switch levers and the spray-valve lever in raised position when the can-assembly is in uppermost position.

Figure 4 represents an elevational view looking generally in the direction of the arrow 4 in Figure 3.

Figure 5 represents an elevational view like that of Figure 3 but showing the can-assembly in somewhat lowered position with the limit-switch levers and the spray-valve lever in lowermost released position.

Figure 6 represents a vertical cross-sectional view through the ice-cans and the insulated air-delivery system.

Figure 7 represents a fragmentary bottom-plan view looking generally in the direction of the arrows 7—7 of Figure 6 showing the manifold arrangement of the air-delivery system.

Figure 8 represents a fragmentary perspective view showing the manner in which the ice-cans are filled with water from the individual nozzles.

Figure 9 represents a perspective view generally like that of Figure 8 but showing the appearance of the parts when the ice-cans are raised to generally horizontal dumping position with the water-nozzles tilted upward and out of the way of the ice-block.

Figure 10 represents a wiring diagram showing the timer and switch connections for controlling the automatic operation of the ice-making machine as they appear during the freezing period—the changes which occur at the end of the freezing period being shown in dash-dot lines.

Figure 10-a represents a view like that of Figure 10 but showing the position of the parts during the thawing period—the changes which occur at the end of the thawing period being shown in dash-dot lines.

Figure 10-b represents a view like that of Figure 10-a but showing the position of the parts during the draining period—the changes which occur at the end of the draining period being shown in dash-dot lines.

Figure 11 represents a vertical cross-sectional view of the water-reservoir in filled position.

Figure 12 represents a horizontal cross-sectional view generally along the line 12—12 of Figure 11.

Figure 13 represents a vertical cross-sectional view generally like that of Figure 11 but showing the appearance of the parts after the outlet valve has been opened and the reservoir partially emptied.

Figure 14 represents a vertical cross-sectional view like those of Figures 11 and 13 but showing the reservoir after it has been fully drained and the outlet-valve reclosed and the filling-valve opened.

Figure 15 represents a side elevational view looking generally in the direction of the arrows 15—15 in Figure 1 but showing different positions of the arm 82 and the operating arm 125.

In one embodiment of the present invention shown generally in Figures 1 and 2, I may provide a frame indicated generally by the reference character 20. The frame 20 may include front

and rear structural members 21 and 22 and left and right elongated structural members 23 and 24 all disposed in a horizontal plane and forming a bottom generally rectangular framework. The frame also includes front and rear members 25 and 26 and left and right members 27 and 28 all lying in a horizontal plane and forming a top generally rectangular framework.

The frame 20 also includes left and right vertical members 29 and 30, left and right rear vertical members 31 and 32, and left and right intermediate vertical members 33 and 34 respectively—the members 21—34 being welded or otherwise appropriately connected to form a generally unitary structure having the necessary strength to support the ice cans and lifting and filling mechanism to be described hereinbelow.

The frame 20 is mounted so that its bottom members are generally at floor-level with the frame straddling a recessed brine-filled freezing-tank 35. The transverse dimension of the freezing-tank may be somewhat less than the length of the side members 23 and 24 so that the front and rear ends of the frame 20 can be appropriately supported outside the freezing-tank 35.

The tank 35 may be considerably elongated so as to accommodate a number of individual frames 20 disposed in side-by-side relationship. That is, while, in Figure 1, a single frame 20 is shown mounted at one end of an elongated freezing-tank 35, it is contemplated that a number of individual frames 20 will, in practice, be mounted above the freezing-tank 35 in side-by-side relationship to each other so that a relatively large number of ice-tanks, individual ice-blocks can be frozen simultaneously in a single freezing-tank.

A pair of journal-blocks 36 and 37 are mounted on the front vertical members 29 and 30 respectively, near the lowermost ends thereof and are adapted rotatably to hold the ends of a horizontal shaft 38.

The shaft 38 extends through an elongated collar 39 in keyed relationship therewith, the collar being fastened to a cradle 40 to provide a pivot for the cradle and the ice-cans to be hereinafter described.

As shown particularly in Figures 1, 2 and 6, the cradle 40 consists essentially of a metal framework which can be tilted from a lowermost generally vertical position (shown in Figure 2 to an uppermost generally horizontal position shown in Figure 1) and which is constructed and arranged to hold a plurality (for example 3) of individual ice-cans 41 in somewhat spaced-apart relationship so as to leave the surface of the nearly-filled ice-cans substantially fully exposed to the cold brine in the freezing tank 35 when the cradle 40 is in its lowermost position of Figure 2 (wherein the ice-can is immersed within the brine to a level slightly below their open upper ends 42 so that the water-level in the can is slightly below the brine-level).

The ice-cans 41 may be of galvanized iron having a rectangular cross-section at the top of 2 x 22 inches and a depth of about 44 inches. However, the dimensions of the ice-cans may be varied if desired. The cans are provided with a smooth interior surface and are preferably downwardly tapered at their front and end-walls 43—a and 43—b to facilitate removal of the ice-blocks formed therein. The ice-cans are held together at their upper ends by a structural flange-member 45 provided at the top of the cradle 40.

which serves as the upper support for the ice-cans in their vertical position.

Each can is provided with a spout or guide-portion 46 at the front portion of its open end 42 to aid in the removal of the ice-block formed in the can.

The cradle is provided with a drain-skirt 47 extending in somewhat spaced-apart relationship to the front end-walls 43-a of the ice-cans 41. That is, the drain-skirt 47 is disposed in generally vertical position when the cradle 40 is lowered as in Figure 2 and in generally horizontal position when the cradle is raised as in Figures 1 and 6.

The drain-skirt is provided with a pair of drain-louvres 48 whose function will be described hereinbelow.

The cradle 40 is also provided with a metal casing 49 which extends downwardly (in Figure 2) in somewhat spaced apart relationship to the rear-end walls 43-b (to which a transverse spacer-bar 50 is welded to assist in maintaining the cans in proper predetermined spaced-apart relationship) and terminates in a bottom manifold-casing 51 which extends underneath the ice-cans as shown in Figures 2, 6 and 7.

The casings 49 and 51 are filled with a good heat-insulating material such as granulated cork, kapok, mineral wool, etc.

An air-supply pipe 52 extends downwardly through the casing 49 and communicates, at its lower end with a manifold 53 which is displaced within the casing 51 and which communicates with the interior of each of the ice-cans 41 through the bottom walls 54 thereof—the upwardly-directed extensions 55 leading to the individual ice-cans being also insulated by individual casings 56 as shown particularly in Figure 6.

The upper end of the air supply pipe 52 connects with a flexible air hose 57 leading to any suitable air-blower 119 driven by a motor 120 at the top of the frame so that air can be continuously bubbled upward through the ice-cans 41 during the freezing operation to provide agitation and to concentrate the impurities within a central core which is removed by a suction-tube (not shown) and replaced by clear water so that the turbid core, usually present in ice-blocks, is minimized.

Mounted at the upper rear-end (in Figure 2) of the cradle 40 are a pair of journals 58 which swivelably support a transversely-extending pipe 59 provided with individual spouts 60 which are constructed and arranged to deliver water to the upper open-ends 42 of the ice-cans when the cans are in the vertical position shown in Figures 2 and 8.

A pair of flexible water-hoses 61 lead upward from the rearwardly-turned ends of the pipe 59 to a T 62. The T 62, in turn, connects with the bottom outlet opening 63 of a water-supply tank or reservoir 64 which is positioned at the uppermost forward end of the frame 20 (resting upon left and right horizontal angle irons 65 and 66 extending intermediate the members 29-33 and 30-34 respectively) and which will be described more fully hereinbelow.

As can be seen particularly in Figure 8, the water delivery spouts 60 are somewhat downwardly inclined when the cans 41 are in vertical filling position so as to direct the water into the individual cans with a minimum of splashing. On the other hand, when the ice-cans are raised to their generally horizontal position, the pipe

59 is free to swivel within the journals 58 (under the added weight of the slackened hoses 61) so as to raise the spouts 60 to more or less horizontal position wherein they are out of the way of the ice-blocks when the latter slide out of the cans.

As indicated particularly in Figures 1 and 2, a yoke 67 is pivotally connected to left and right angle irons 68 and 69, welded or otherwise fastened to the rear edges of the two outermost ice-cans at the bottom of the cradle 40. A flexible chain 70 leads upward from the yoke 67 to a generally conventional chain-hoist 71 supported from a cross-bar 72 located at the very top of the frame 20 generally adjacent the rear of said frame.

The chain-hoist 71 is driven by a conventional reversing motor (not shown) which is controlled by a rocker-arm 134. The rocker-arm 134 is centrally pivoted and is operatively connected to a 3-way switch (not shown) so that when the rocker-arm is in its normal generally horizontal position, the 3-way switch will be open and the hoist motor stopped. When one end of the rocker-arm 134 is pulled downward, the 3-way switch is thrown to the position starting the motor in one direction so as to lower the hoist. When the other end of the rocker-arm is pulled downward, the 3-way switch is thrown to position starting the motor in the opposite direction so as to raise the hoist.

While the rocker-arm can be operated manually, it is preferred to provide a pair of solenoid controls 135 and 136.

35 The solenoid control 135 includes an armature 137 which is suspended from one end of the rocker-arm 134 and which is pulled downward when the solenoid is energized, thereby to tilt the rocker-arm to hoist-raising position.

40 The solenoid 136 includes an armature 138 which is suspended from the other end of the rocker arm 134 and which is pulled downward when the solenoid is energized so as oppositely to tilt the rocker-arm to hoist-lowering position.

45 The rocker-arm 134 is suitably spring-tensioned so that it automatically returns to its normal horizontal position (wherein the hoist motor is stopped) when neither of the solenoids 50 135 and 136 is energized. It is apparent, of course, that the solenoids should be energized alternatively, not simultaneously (since simultaneous downward pull on both armatures would produce no tilting of the rocker-arm and would simply burn out the coils of the solenoids).

55 A pair of switches 132 and 133 are provided to energize the solenoids 135 and 136 respectively when the ice-making machine of the present invention is being run in "manual" operation (as distinguished from the "automatic" operation to be described hereinbelow).

The chain hoist can be operated to raise and lower the cradle 40. That is, when the chain 70 is lowered as far as it will go, the cradle is in generally vertical position shown in Figure 2 (wherein the individual ice-cans are immersed in the brine of the freezing tank as discussed hereinabove). When the chain hoist 71 is operated to raise the chain 70, the yoke 67 will tend to raise the rear lower edge of the cradle 40 which swings in an arc about the shaft 38 so that it gradually shifts until it assumes the generally horizontal position shown in Figures 1 and 6. Actually, in its uppermost position, the rear-end of the cradle 40 is raised somewhat higher than the

front-end, so that the ice-cans are slightly forwardly and downwardly inclined to permit the ice-blocks to slide out freely through the open ends 42 after they have been thawed loose as will be described hereinbelow.

As shown particularly in Figure 2, a plurality (for example 3) of somewhat forwardly and downwardly inclined thaw-pipes 73 are positioned below the water supply tank 64 so as to be located directly above the end walls 43—b of the ice-cans 41 when the cradle 40 is the uppermost position shown in Figure 1.

Each of the thaw-pipes 73 is provided with a plurality of sprinkler-heads 74 and is connected to a water line 75 in which is located a valve 76 provided with an elongated control arm 77 extending across the path of travel of the yoke 67.

The valve 76 is normally tensioned to closed position, wherein the arm 77 is lowered. However, when the yoke 67 is raised to uppermost position, it contacts and raises the control-arm 77 in the manner shown in Figure 3 so as to open the valve 76 and to admit water to the thaw-pipes 73, whereby the thawing water is free to flow through the sprinkler-heads 74 on to the ice-cans 41 (which are then in their uppermost position shown in Figure 1). The action of the thawing water loosens the ice-blocks and permits them to slide out of the individual ice-cans 41 through the open ends 42 thereof.

The thawing water falls down around the walls of the individual ice-cans and on to the drain-skirt 47 from which it flows forwardly and downwardly into a gutter or drain 78. Due to the forward and downward inclination of the drain-skirt 47, as shown in dash-dot lines in Figure 6, the drain water is kept from falling into the brine tank through the drain-louvres 48, so that dilution of the brine is prevented.

On the other hand, when the cradle is first being raised from the brine tank, the brine adhering to the sides of the ice-cans 41 is free to drain back into the brine tank through the drain-louvres 48 due to their downward and rearward inclination, as shown in solid lines in Figure 6.

When the yoke 67 is lowered slightly from the uppermost position shown in Figures 3 and 4 to the position shown in Figure 5, the valve 76 automatically closes to stop the flow of thawing water through the sprinkler-heads 74.

The cradle 40 is also provided with left and right splash-shields 79 and 80 which direct the thawing water into the drain-skirt 47 and prevent the water from splashing into the brine tank and diluting the brine.

While, as will be described hereinbelow, the present invention contemplates fully-automatic operation of the ice-making machine of the present invention, the machine can, optionally, be operated step-by-step non-automatically.

Thus, starting with the cradle and ice-cans in lowered vertical position as shown in Figure 2, the non-automatic operation of the machine of the present invention is as follows.

The ice-cans 41 are first filled with water from the water supply tank 64 (through the T 62, the hoses 61, the pipe 59 and the spouts 60), after which the air is turned on and sent to the ice-cans (through the hose 57 and the pipes 52, 53 and 55). The filled ice-cans are permitted to remain in the freezing brine tank, with air agitation, for a time sufficient to freeze the water in the cans (except for the central turbid core which is ultimately sucked out and replaced with clean water which freezes to fill up the opening thus

left). Due to the relatively small transverse dimension of the individual ice-cans 41, thereby exposing a much greater cooling area per pound of water to be frozen, they can be fully frozen in as little as two hours (as compared to 40-50 hours required to freeze a standard-sized ice-can which has a transverse dimension of about 11 inches). After the freezing operation has been completed, the chain-hoist is started to raise the cradle to the uppermost position shown in Figure 1, at which point the chain hoist is stopped. In this uppermost position the control-arm 77 of the valve 76 is maintained in the raised position shown in Figure 3 thereby permitting thawing water to flow to the thaw-pipe 73 and to the sprinkler-heads 74.

The flow of thawing water is permitted to continue for about seven minutes, after which the chain hoist is operated to lower the cradle 40 slightly, thereby permitting the control-arm 77 to move to the closed position shown in Figure 5 so as to stop the further flow of thawing water.

The cradle is kept in this last named position for about two minutes to permit drainage of the thawing water from the sides of the cans on to the drain-skirt 47 and into the gutter 78.

After the thawing operation, the ice-blocks will slide out from the cans through the open ends 42 thereof under the action of gravity. The ice-blocks can then be transported; by any appropriate conveyor belt or the like (not shown) to any suitable ice-storage room for future shipment or for use on the premises.

After the ice-cans have been thus emptied, the chain hoist is started to lower the cradle 40 back to its starting position shown in Figure 2 after which water is again introduced into the individual ice-cans from the reservoir (which has been refilled during the preceding freezing period).

Where opaque ice is to be manufactured (i. e. where the ice is to be used for industrial purposes and not for home consumption, so that clarity is unimportant) air-agitation can be dispensed with. In such case, the air-supply pipe 52 and the insulated casing 51, etc., can be omitted from the cradle and the entire volume of water in the individual ice-cans may be frozen solid (without removal of the central turbid core).

The freezing, draining and thawing times given herein are solely for purposes of illustration and it should be understood that these times can be varied appreciably depending upon the temperature of the brine and other conditions. Thus, for example, the freezing may require as little as 1½ hours and as much as 3 hours. The draining may require one to three minutes or more. The thawing may require from 5 to 10 minutes.

The preferred embodiment of the present invention includes means for automatically filling the lowered ice-cans 41 with a predetermined quantity of water to be frozen, means for automatically starting the chain-hoist 78 to raise the cradle 40 after the ice-cans 41 have been immersed in the freezing tank 35 for two hours (or other suitable time necessary to complete the freezing of the water in the ice-cans), means for stopping the chain-hoist when the cradle has reached the uppermost position shown in Figure 3 (wherein the valve 76 is opened, permitting thawing-water to flow over the ice-cans from the sprinkler-heads 74), means for automatically starting and stopping the chain-hoist so as to lower the cradle to the position shown in Figure

5 after seven minutes (or other suitable thawing-time) has elapsed, means for starting the chain-hoist after two minutes (or other suitable draining time) has elapsed so as to lower the cradle to the original starting position shown in Figure 2, and means for automatically emptying the water from the tank 64 (which is then automatically re-filled with a predetermined quantity of water for the next freezing operation) into the ice-cans 41 as soon as the ice-cans return to their lowered vertical position shown in Figure 2, and so on.

The automatic control means referred to hereinabove include a novel arrangement of automatic timers and switches, for controlling the motor of the chain-hoist, as shown schematically in the wiring diagram of Figure 10, and also include novel means, shown particularly in Figures 11-14, for automatically filling the water-supply tank 64 with a predetermined quantity of water and for automatically opening an outlet valve to permit the water to drain into the ice-cans as soon as the emptied ice-cans reach the lowered vertical position of Figure 2.

Referring first to the novel arrangement of automatic timers and limit-switches as shown schematically, in Figures 10, 10-a and 10-b, which are placed in operation when a double-pole, double-throw switch 131 is set to provide "automatic" operation (as distinguished from "manual" operation), the present invention contemplates a limit-switch 81 which is connected in series with the down-solenoid 136 and which is mounted at the bottom of the frame 20 adjacent the front right-hand corner thereof (as shown particularly in Figure 1) and which is provided with a control-arm 81-a normally tensioned to uppermost position wherein the switch is closed. As the cradle 40 swings downward from the uppermost position shown in Figure 1, an arm 82 keyed to the right-hand end of the shaft 22 swings clockwise (in Figure 1) and downward so that when the cradle reaches its lowermost vertical position, the arm 82 depresses the control-arm 81-a as shown in dash-dot lines in Figure 15, to open the switch 81 and to de-energize the down-solenoid 136, thereby to stop the downward movement of the hoist 71. The limit-switch 81 is kept in its open position during the freezing period (which may run for two hours or any other appropriate time).

An automatic freeze-timer 83 of generally conventional construction (as, for example, a series 2800 timer, manufactured by Automatic Temperature Control Co., Inc., of Philadelphia, Pa.) includes a single-throw type switch 200 which, during the freezing period, is in the closed position shown in solid lines in Figure 10, and also includes a double-throw type switch 201 which, during the freezing period, is in the upper position shown in solid lines in Figure 10.

At the end of the predetermined freezing period, the switch 200 is flipped to the open position shown in dash-dot lines in Figure 2 thereby breaking the circuit to the motor 202 of the freeze-timer 83 so as to stop the motor.

At the same time, the switch 201 is flipped to the lower position shown in dash-dot lines in Figure 10 thereby closing a circuit energizing the clutch 203 of a thaw-timer 86 and resulting in movement of a single-throw type switch 204 from the open position shown in solid lines in Figure 10 to the closed position shown in dash-dot lines in Figure 10 and also resulting in movement of a double-throw type switch 205 from the upper position shown in solid lines in Figure 10 to the

lower position shown in dash-dot lines in Figure 10.

The closing of the switch 204 completes a circuit energizing the motor 206 of the thaw-timer 86 which is set for seven minutes or any other desired thawing time.

Downward movement of the switch 205, as aforesaid, closes a circuit energizing the up-solenoid 135 so as to start the hoist 71 upward and to raise the cradle 40 and the ice-cans 41 from the freezing tank 35.

The chain hoist 71 continues to run until the yoke of the cradle 40 contacts and lifts the downwardly-tensioned control-arm 84 of a normally-closed limit-switch 85, connected in series with the up-solenoid 135 so as to open the switch 85 and to de-energize the up-solenoid 135 and thereby to stop upward movement of the hoist 71 and the cradle 40.

20 In this uppermost position (as shown in Figure 3 and also shown in solid lines in Figure 4), the control-arm 77 of the valve 76 has also been raised to open the valve 76 in the manner described hereinabove so as to send water to the thaw-pipes 73, thereby permitting water to flow over the raised ice-cans 41.

This upward movement of the yoke 67 also raises the downwardly-tensioned control-arm 87 of a drain limit-switch 88 so as to shift the limit-switch 88 from its normal position shown in Figure 10 to the position shown in Figure 10-a (and also shown in solid lines in Figure 4).

As indicated by the solid lines in Figure 10-a, both solenoids 135 and 136 are de-energized to maintain the hoist and the cradle in uppermost position during the thawing period.

At the end of the thawing period, the switch

204 is moved from its closed position (as shown in solid lines in Figure 10-a) to its open position (shown in dash-dot lines in Figure 10-a) so as to break the circuit to the motor 206 of the thaw timer 86 and to stop the motor. The switch 205 is also moved from its lower position (shown in solid lines in Figure 10-a) to its upper position

45 (shown in dash-dot lines in Figure 10-a) thereby closing a circuit energizing the clutch 207 of the freeze-timer 83 resulting in movement of the switches 200 and 201 from the solid-line positions to the dash-dot line positions in Figure 10-a. That is, the switch 200 is closed to re-start the motor 202 of the freeze-timer (which is set for two hours or any other desired freezing period) while the switch 201 is moved to upper position closing a circuit energizing the down-solenoid 136 (as indicated in dash-dot lines in Figure 10-a) and resulting in downward movement of the cradle 40.

However, when the cradle 40 is moved downward a relatively short distance to the position shown in dash-dot lines in Figure 4 (so as to release the control-arm 77 and close the valve 76), the control-arm 87 is released so that the drain limit-switch 88 automatically returns to its original position as shown in Figure 10-b (and also shown in dash-dot lines in Figure 4) which breaks the circuit to the down-solenoid 136 so as to stop further downward movement of the cradle 40. This movement of the switch 88 to the

70 position shown in Figure 10-b also closes a circuit to a drain-timer 89 (which is set for two minutes or any other suitable draining period). That is, closing of this last-mentioned circuit energizes the drain-timer clutch 208 which moves a double-throw switch 209 to the position shown

in solid lines in Figure 10-b thereby closing the circuit to start the drain-timer motor 210.

While this preliminary downward movement of the cradle 40 has also released the control-arm 84 and re-closed the limit-switch 85 in the circuit of the up-solenoid 135, the up-solenoid nevertheless remains de-energized because its circuit is kept open by the switch 201 of the freeze-timer; the switch 201 being in the upper position shown in Figure 10-b during the freezing period.

At the end of the draining period, the drain-timer switch 209 is flipped to the dash-dot line position shown in Figure 10-b thereby breaking the circuit to the motor 213 and, at the same time, closing a circuit to the down-solenoid 136, so as to re-start the downward movement of the hoist and cradle and thereby to lower the ice-cans into the freezing tank.

This downward movement continues until the limit-switch 81 is again opened so as to break the circuit to the down-solenoid 136 and to stop the hoist and the cradle in the lowermost position shown in Figure 2.

In this position, the ice-cans are automatically refilled from the water-supply tank 64 (as will be described hereinbelow), and are kept in the brine-tank until the end of the freezing period, at which time the switches 200 and 201 are flipped from their solid-line positions to their dash-dot line positions in Figure 10 to repeat the cycle of operations (i. e. raising, thawing, partially lowering, draining, further lowering and freezing).

Considering now the automatic filling operation for the water-supply tank 64, the normal closed filled position of the tank is shown in Figure 11 wherein the outlet opening 63 is closed by a valve-member 90 mounted on a vertical stem 91 which extends through a guide-member 92 and is normally urged to lowermost closed position by a helical spring 93.

With the water in the tank 64 at its predetermined upper level, the normally downward-tensioned control-arm 94 of a normally-open inlet-valve 95 is raised to uppermost valve-closing position by a ball-float 96. The ball-float 96 is provided with an upwardly-extending rod 97 which extends intermediate the bifurcated end 98 of the control-arm 94 and also intermediate the oppositely-directed bifurcated end 99 of a lever 100 to be described hereinbelow. The upper end of the rod 97 is provided with an enlarged head 101 whose function will be described below.

The lever 100 is pivotally mounted intermediate its ends upon a horizontal shaft 102 supported between end-brackets 103 fastened to a structural member 104 extending transversely across the top of the tank 64. The other (forwardly-extending) end of the lever 100 is notched on its underside as at 105 and is normally urged to downward position (counter-clockwise in Figures 11 and 13) by a coil spring 106 whose other end is fastened to the structural member 104.

Also pivotally mounted on the shaft 102 is a restraining arm 107 whose rearmost end 108 is provided with a closed loop 109 which passes underneath the control-arm 94 of the inlet-valve 95.

The forward end 110 of the restraining arm 107 is connected, by a chain 111, to one arm 112 of a generally L-shaped detent or pawl member 113. The arm 112 is fixedly mounted, intermediate its ends, upon a transversely-extending rotatable shaft 114 journaled in blocks 115 mounted at the top of the tank 64.

The other arm 116 of the pawl member 113 is disposed below and in alignment with the forward end of the lever 100 when the tank is in its normal filled position, as shown in Figure 11. However, when the shaft 114 and the pawl member 113 are rotated counter-clockwise, the arm 116 swings up until it contacts the forward end of the lever 100 and rotates it clockwise (against the action of the spring 106) to a point at which the arm 116 seats itself within the notch 105 as shown in Figure 13.

This counter-clockwise rotation of the pawl member 113 also results in a counter-clockwise rotation of the restraining arm 107 by the action of the chain 111, as indicated in Figure 13.

Mounted upon the shaft 114, on either side of the valve stem 91, are a pair of cam discs 117 against which downwardly bear a pair of oppositely-extending horizontal cam-followers 118 mounted on the valve stem 91.

When the tank 64 is filled and the valve member 90 is in its lowermost closed position, the cam-followers 118 contact low-points of the cam discs 117. However, when the shaft 114 is rotated counter-clockwise from the position shown in Figure 11, the cam discs 117 swing to raise the cam-followers 118, thereby to lift the stem 91 (against the spring 93) and to open the valve member 90.

As shown particularly in Figure 1, the right-hand end of the shaft 114 is provided with a crank 121, to the free end of which is pivotally connected the uppermost end of a generally vertical crank-shaft 122. The crank-shaft 122 extends downwardly along the right-hand side of the frame 20—its lowermost end extending through an oversize slot 123 formed somewhat inwardly of one end 124 of a generally horizontal operating arm 125. A transverse retaining-pin 126 is provided at the lowermost end of the crank-shaft 122 below the operating arm 125.

The operating arm 125 is pivotally mounted intermediate its ends within a bracket 127 supported upon the bottom right-hand horizontal frame member 24; the other (rear) end of the operating arm 125 being provided with a weight 128 which normally urges the operating arm 125 clockwise to the position shown in Figure 1 wherein the slotted end 124 is maintained somewhat above the lowermost end of the crank-shaft 122. This clockwise rotation of the operating arm 125 is limited by a stop-member 129 mounted at the forward edge of the bracket 127 somewhat above the arm 125.

The operating arm 125 is disposed in generally the same vertical plane as the arm 82 on the shaft 38 and the forward slotted end 124 of the arm 125 extends within the arc of travel of the arm 82 so that clockwise (in Figure 1) rotation of the shaft 38 and the arm 82 will cause the arm 82 to contact the end 124 and to tilt the operating arm 125 counter-clockwise until it strikes the retaining-pin 126 and thereafter moves the crankshaft 122 downward to result in counter-clockwise rotation of the crank 121 and the shaft 114.

In operation, when the cradle 40 begins its downward movement following the dumping of the ice blocks (at the end of the two-minute draining period), the arm 82 contacts the end 124 and momentarily tilts the operating arm 125, as shown in solid lines in Figure 15 (which results in downward movement of the crank-shaft 122 and counter-clockwise rotation of the crank 121 and the shaft 114 as described hereinabove).

As the shaft 38 and the arm 82 continue to move clockwise, to the position shown in dash-dot lines in Figure 15, the arm 82 moves clear of the end 124 thereby releasing the operating arm 125 and permitting it to tilt clockwise (under the action of the weight 128) to its original position—the arm 82 thereafter continuing to move downward until it operates the limit-switch 81 as described hereinabove.

When the crank 121 and the shaft 114 are rotated counter-clockwise as described above, the cam-discs 117 operate to raise the cam-followers 118 and the shaft 114 from the position shown in Figure 11 to that shown in Figure 13. During this rotation, the detent member 113 is also swung counter-clockwise to the position shown in Figure 13 wherein its arm 116 is engaged within the notch 105 and holds the lever 100 in generally horizontal clockwise-rotated position, and wherein its arm 112 is moved counter-clockwise and downward to pull the chain 111 and to tilt the restraining arm 107 counter-clockwise. In this position, the loop 109 on the rearmost end 108 of the restraining arm 107 is raised to maintain the control-arm 94 of the inlet valve 95 in its uppermost valve-closing position, even after the ball-float 96 moves downward, as indicated in Figure 13, as the water-level drops (due to flow of water through the opened outlet valve, the T 62, the hoses 61 and the spouts 60, to the ice-cans 41 as described above).

In this way, only the predetermined amount of water is delivered from the tank 64 to the ice-cans 41—no additional water being delivered to the tank 64 from the inlet valve 95 during the time required to drain the storage tank.

However, as the level of water continues to drop, the ball-float 96 is lowered to the point at which the enlarged upper head 101 on the rod 97 contacts the bifurcated end 99 of the lever 100 and tilts it clockwise to the position shown in Figure 14 so as to raise the notched end 105 above the arm 116, thereby releasing the detent member and permitting the shaft 114 and its associated cam-discs 117 to rotate clockwise (due to its weight-distribution). This clockwise rotation of the cam-discs 117 permits the valve member 90 to close under the action of its spring 93 so as to return to the position shown in Figure 11.

During this clockwise rotation of the shaft 114, the crank-shaft 122 is raised back to the original position shown in Figure 1.

This clockwise rotation of the shaft 114 and its associated detent member 113 also slackens the chain 111, thereby permitting the restraining arm 107 to move clockwise (due to its weight-distribution) so as to lower the loop 109 and to release the control-arm 94 of the inlet-valve 95 which thereupon drops to its normal lowermost position opening the inlet-valve to begin the refilling of the tank 64.

As the level of water in the tank rises, the ball-float 96 gradually moves upward from the position shown in Figure 14 to that shown in Figure 11 at which it forces the control-arm 94 to its uppermost valve-closing position, stopping further flow of water.

The tank 64 then remains in the filled position of Figure 11 until the freezing, thawing, and dumping operations have been completed and the cradle 40 has once again been lowered to the filling position whereupon the clockwise rotation of the arm 82 trips the operating arm 125 to repeat the cycle.

As shown particularly in Figure 2, the timers 83, 86 and 89, and the switches 131, 132 and 133 are mounted in a cabinet 130 located at the rear of the frame 20 so that they are easily accessible for adjustment in the event the timing periods require variation.

As mentioned hereinabove, the number of ice-cans 41 carried by the cradle 40 can be varied. The dimensions of the ice-cans can similarly be varied, as for example by providing greater transverse dimension which would increase the capacity of the individual cans but would require longer freezing time.

Indeed, the cradle 40 could readily be modified to take a single "standard" ice-can which is about 11 inches in transverse dimension and requires 40-50 hours to freeze. This longer freezing time can be attained by suitable adjustment of the timer 83.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention, I claim as new and desire to protect by Letters Patent:

1. An ice-making machine comprising a frame mounted above a brine-filled freezing-tank, a cradle pivotally-mounted adjacent the bottom of said frame, one or more open-top ice-cans carried by said cradle, a reversible power-hoist mounted at the top of said frame and having a chain or the like connected to the cradle whereby said ice-cans can be lowered to generally upright position partly immersed within the freezing-tank and whereby said ice-cans can be raised to generally horizontal position above the freezing-tank with their open-tops somewhat downwardly-inclined, one or more thaw-pipes mounted on said frame and constructed and arranged to spray thawing-water over said ice-cans in their last-mentioned generally horizontal position so as to free the ice-blocks formed therein and to permit the ice-blocks to slide out of the ice-cans through their open-tops, said frame being provided with a splash-shield to keep the thawing-water from running into the freezing-tank, a water-reservoir mounted adjacent the top of said frame and constructed and arranged to fill the ice-cans with water-to-be-frozen by gravity after the ice-cans have been lowered to their generally upright position, and a thermal-insulated air-pipe carried by said cradle and communicating with the bottoms of said ice-cans whereby air can be bubbled through the water-filled ice-cans during the freezing operation.

2. An ice-making machine comprising a frame mounted above a brine-filled freezing-tank, a cradle pivotally-mounted adjacent the bottom of said frame, one or more open-top ice-cans carried by said cradle, a reversible power-hoist mounted at the top of said frame and having a chain or the like connected to the cradle whereby said ice-cans can be lowered to generally upright position partly immersed within the freezing-tank and whereby said ice-cans can be raised to generally horizontal position above the freezing-tank with their open-tops somewhat downwardly-inclined, one or more thaw-pipes mounted on said frame and constructed and arranged to spray thawing-water over said ice-cans in their

last-mentioned generally horizontal position so as to free the ice-blocks formed therein and to permit the ice-blocks to slide out of the ice-cans through their open-tops, and a water-reservoir mounted adjacent the top of said frame and constructed and arranged to fill the ice-cans with water-to-be-frozen by gravity after the ice-cans have been lowered to their generally upright position.

3. An ice-making machine comprising a frame mounted above a brine-filled freezing-tank, a cradle pivotally-mounted adjacent the bottom of said frame, a plurality of relatively thin open-top ice-cans having downwardly-tapered end-walls mounted upon said cradle in generally parallel spaced-apart relationship, a reversible power-hoist mounted at the top of said frame and having a chain or the like connected to the cradle whereby said ice-cans can be lowered to generally upright position partly immersed within the freezing-tank and whereby said ice-cans can be raised to generally horizontal position above the freezing-tank with their open-tops somewhat downwardly-inclined, one or more thaw-pipes mounted on said frame and constructed and arranged to spray thawing-water over said ice-cans in their last-mentioned generally horizontal position so as to free the ice-blocks formed therein and to permit the ice-blocks to slide out of the ice-cans through their open-tops, and a water-reservoir mounted adjacent the top of said frame and constructed and arranged to fill the ice-cans with water-to-be-frozen by gravity after the ice-cans have been lowered to their generally upright position.

4. An ice-making machine comprising a frame mounted above a brine-filled freezing-tank, a cradle pivotally-mounted adjacent the bottom of said frame, a plurality of relatively thin open-top ice-cans having downwardly-tapered end-walls mounted upon said cradle in generally parallel space-apart relationship, a reversible power-hoist mounted at the top of said frame and having a chain or the like connected to the cradle whereby said ice-cans can be lowered to generally upright position partly immersed within the freezing-tank and whereby said ice-cans can be raised to generally horizontal position above the freezing-tank with their open-tops somewhat downwardly-inclined, one or more thaw-pipes mounted on said frame and constructed and arranged to spray thawing-water over said ice-cans in their last-mentioned generally horizontal position so as to free the ice-blocks formed therein and to permit the ice-blocks to slide out of the ice-cans through their open-tops, said frame being provided with a splash-shield and said cradle with a drain-skirt having inclined drain-louvers constructed and arranged to permit brine to drain from the outside of the ice-cans back into the freezing-tank during the raising of the ice-cans while preventing thawing-water from running into the freezing-tank when the ice-cans are in their generally horizontal position, and a thermal-insulated air-pipe carried by said cradle and communicating with the bottoms of said ice-cans whereby air can be bubbled through the water-filled ice-cans during the freezing operation.

5. An automatic ice-making machine comprising a frame mounted above a brine-filled freezing-tank, a cradle pivotally mounted adjacent the bottom of said frame, one or more open-top ice-cans carried by said cradle, a power-hoist mounted at the top of said frame and having a chain or the like connected to the cradle where-

by said ice-cans can be lowered to generally upright position partly immersed within the freezing-tank and whereby said ice-cans can be raised to generally horizontal position above the freezing-tank with their open-tops somewhat downwardly-inclined, one or more thaw-pipes mounted on said frame and constructed and arranged to spray thawing-water over the ice-cans in their last-mentioned generally horizontal position so as to free the ice-blocks formed therein and to permit the ice-blocks to slide out of the ice-cans through their open-tops, a control-valve operatively connected to said thaw-pipes, a water-reservoir mounted adjacent the top of said frame and having an outlet valve, a delivery line leading from the outlet valve to the ice-cans and a float-operated inlet valve, a control-arm connected to said cradle and tiltable therewith, trip-mechanism actuated by said control-arm for opening the outlet valve of the water-reservoir when the ice-cans reach their lowered generally upright position, and for automatically closing said outlet valve when said reservoir has been emptied, and mechanism for automatically operating the power-hoist and the control-valve, said mechanism including a freeze-timer and a thaw-timer operatively interconnected so that the freeze-timer automatically starts the thaw-timer at the end of the freezing period and the thaw-timer automatically starts the freeze-timer at the end of the thawing period, a normally-closed limit-switch constructed and arranged to be opened when said cradle is raised to uppermost position thereby to stop upward movement of the power-hoist, said control-valve being normally closed but being constructed and arranged to be opened when said cradle reaches said uppermost position, a drain-timer, a second limit-switch constructed and arranged to be actuated in one direction when said cradle reaches its uppermost position, said thaw-timer being constructed and arranged to start downward movement of the power-hoist from the uppermost position at the end of its timing period, said second limit-switch being constructed and arranged to be actuated in the other direction after said cradle has been lowered somewhat from its uppermost position thereby to stop downward movement of said power-hoist and simultaneously to start the drain-timer, said drain-timer being constructed and arranged automatically to re-start the downward movement of the power-hoist at the end of its timing period, and a third normally-closed limit-switch constructed and arranged to be opened when said cradle reaches its lowermost position thereby to stop the downward movement of the power-hoist, said freeze-timer being constructed and arranged to start upward movement of the power-hoist at the end of its timing period.

6. A construction according to claim 5 wherein the power-hoist is provided with a centrally-pivoted rocker-arm normally tensioned to generally horizontal open position and wherein a solenoid-control is connected to one end of said rocker-arm, said solenoid-control being constructed and arranged to tilt said rocker-arm in one direction, when energized, to cause upward movement of said power-hoist, and wherein a second solenoid-control is connected to the other end of said rocker-arm, said second solenoid-control being constructed and arranged to tilt the rocker-arm in the other direction when energized, to cause downward movement of said power-hoist, said first-mentioned solenoid-control being constructed and arranged to be energized by the freeze-

timer at the end of its timing period and to be de-energized upon opening of the first-mentioned limit-switch, said second-mentioned solenoid-control being constructed and arranged to be energized by said thaw-timer at the end of its timing period and to be de-energized upon movement of the second limit-switch in its other direction and to be re-energized by said drain-timer at the end of its timing period and to be again de-energized upon opening of the third limit-switch.

7. An ice-making machine comprising a frame mounted above a brine-filled freezing-tank, a cradle pivotally-mounted adjacent the bottom of said frame, one or more open-top ice-cans carried by said cradle, a reversible power-hoist mounted at the top of said frame and having a chain or the like connected to the cradle whereby said ice-cans can be lowered to generally upright position partly immersed within the freezing-tank and whereby said ice-cans can be raised to generally horizontal position above the freezing-tank with their open-tops somewhat downwardly-inclined, one or more thaw-pipes mounted on said frame and constructed and arranged to spray thawing-water over said ice-cans in their last-mentioned generally horizontal position so as to free the ice-blocks formed therein and to permit the ice-blocks to slide out of the ice-cans through their open-tops, a water-reservoir mounted adjacent the top of said frame and having an outlet valve, a delivery line leading from the outlet valve to the ice-cans, an inlet valve, and float mechanism operatively connected to said inlet valve and constructed and arranged to close said inlet valve when the water within the reservoir reaches a predetermined level, a control-arm connected to said cradle and tiltable therewith, and trip-mechanism actuated by said control-arm for opening the outlet valve of the water-reservoir when the ice-cans reach their lowered generally upright position, and for automatically closing said outlet valve when said reservoir has been emptied.

8. An ice-making machine comprising a frame mounted above a brine-filled freezing-tank, a cradle pivotally-mounted adjacent the bottom of said frame, one or more open-top ice-cans carried by said cradle, a reversible power-hoist mounted at the top of said frame and having a chain or the like connected to the cradle whereby said ice-cans can be lowered to generally upright position partly immersed within the

freezing-tank and whereby said ice-cans can be raised to generally horizontal position above the freezing-tank with their open-tops somewhat downwardly-inclined, one or more thaw-pipes mounted on said frame and constructed and arranged to spray thawing-water over said ice-cans in their last-mentioned generally horizontal position so as to free the ice-blocks formed therein and to permit the ice-blocks to slide out of the ice-cans through their open-tops, a water-reservoir mounted adjacent the top of said frame and having an outlet valve, a delivery line leading from the outlet valve to the ice-cans, an inlet valve, and float-mechanism operatively connected to said inlet valve and constructed and arranged to close said inlet valve when the water within the reservoir reaches a predetermined level, a control-arm connected to said cradle and tiltable therewith, trip-mechanism actuated by said control-arm for opening the outlet valve of the water-reservoir when the ice-cans reach their lowered generally upright position, and for automatically closing said outlet valve when said reservoir has been emptied, and latch-mechanism constructed and arranged to maintain the inlet valve in closed position and to maintain the outlet valve in open position until the water-reservoir has been substantially emptied adn thereafter to permit closing of the outlet valve and opening of the inlet valve.

9. A construction according to claim 5 wherein the water-reservoir is provided with an inlet-valve and with mechanism constructed and arranged to close said inlet valve when the water within the reservoir rises to a predetermined level and to open said inlet valve only when the reservoir has been substantially emptied.
